(57) **CLAIM**

The ornamental design for a linear actuator, as shown and described.

DESCRIPTION

FIG. 1 is a perspective view of a linear actuator showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is second perspective view showing the linear actuator; and,

FIG. 9 is third perspective view showing the linear actuator.

1 Claim, 8 Drawing SheetsFIG. 1

FIG.2

FIG. 3

FIG.5

FIG.4

FIG. 6

FIG.7

FIG. 9
